ATTORNEYS

UNITED STATES PATENT OFFICE

OTTO T. MAURER, OF NEW YORK, N. Y.

PACKAGE-OPENING DEVICE

Application filed June 18, 1929. Serial No. 371,849.

This invention relates to the class of sealed packages, and relates more particularly to means for breaking the seal of the package, and for forming an opening therein, whereby the contents of the package may be readily removed.

The principal object of the invention is the provision of means of the indicated character which affords ends integral with the material of the inner casing or wrapper of the package and which protrude exteriorly thereof, whereby a pull on the protruding ends will break the seal of the package and remove portions thereof to form an opening in the package through which the contents thereof may be removed.

The nature of the invention and its distinguishing features and advantages will appear when the following specification is read in connection with the accompanying drawing, in which—

Figure 1 is a perspective view of a cigarette package selected to illustrate the invention, the package being shown in sealed condition.

Fig. 2 is a perspective view of the package shown opened.

Fig. 3 is an enlarged central vertical section of the package with portions broken away.

Fig. 4 is a fragmentary perspective view showing certain features of the invention.

Fig. 5 is a fragmentary perspective view showing certain features of the inner wrapper sheet.

In the present instance by way of example a cigarette package is selected to illustrate the present invention. A package of this kind includes wrapper sheets 10 and 11, the former being of paper and the latter being of tinfoil laid on the outside of the sheet 10. The sheets 10 and 11 are adapted to be folded to form a casing to completely envelop the cigarettes. A wrapper sheet 12 of paper is folded to form a pouch-like body or cover

open at one end to receive the casing aforesaid. The package also includes a wrapper sheet of transparent paper 13 adapted to be folded about the pouch-like cover on the outside thereof to completely seal the package.

Attention is also called to the fact that in the

sale of tobacco products it is necessary to apply a revenue stamp, and such revenue stamp is designated 14 and has the opposite ends thereof pasted respectively to the sides of the pouch-like cover with the intermediate portion thereof extending over the end of the casing which envelops the cigarettes. It will be apparent that the stamp 14 will occur inside of the wrapper 13.

In accordance with the present invention each of the sheets of material 10, 11 and 13 will be slotted in two of the folds respectively of the opposite side portions. The manner in which these slits occur in the folds is illustrated in Figs. 4 and 5, and the latter figure shows the inner wrapper sheet which is folded directly about the cigarettes indicated at 15 to completely envelop the same. The slits are designated 16, and it will be understood that the slits in the sheets 10 and 11 occur at similar points therein so as to be in registry with each other. The slits 16 in the sheets 10 and 11 in their folded condition will occur beneath the stamp 14 in spaced relation with respect to one edge thereof as shown most clearly in Fig. 3. The inner wrapper sheet 10 is so cut as to present tabs 17 which will be disposed side by side when the sheet 10 is folded as shown in Fig. 1. The wrapper sheet 10 also has lines of perforations 18 therein which extend from the slits 16 to the edges of the folds having the tabs 17. In this manner the wrapper sheet 10 will have partly severed portions which are designated 19. The tabs 17 are of such length as to be extended through the slits 16 in the wrapper sheets 10 and 11, and through the slits 16 of the outside wrapper sheet to present protruding ends exterior of the package. The slits 16 in the outside wrapper sheet 13 occur substantially coincidental with one edge of stamp 14.

From the foregoing it will be apparent that when the protruding ends of the tabs 17 are gripped, the tabs may be pulled first in one direction causing the stamp 14 to be broken, and then by exerting a pull on the tabs 17 in an opposite direction the outer wrapper formed of the sheet 13 will be broken, and at the same time the partly sev.

ered portions 19 will be torn from the inner wrapper sheet 10 forming an opening in the package through which the cigarettes may be removed.

5 I claim:

1. A sealed package of the class described including an inner wrapper sheet of paper completely enveloping the contents of the package, an outer wrapper sheet of paper sealing the package, slits in the folds of the wrapper sheets, the slits in the folds of the outer sheet being offset with respect to the slits in the folds of the inner sheet, said inner sheet having partly severed portions, tabs integral with said portions, said tabs being extended outwardly through said slits to present protruding ends exteriorly of the package, whereby a pull on said protruding ends of the tabs will break the seal of the package, and will also detach said portions, to form an opening in the package through which the contents of the package may be removed.
2. A sealed package of the class described including a contents enveloping paper inner wrapper, a paper pouch-like cover on the outside of said wrapper, said cover being open at one end, a revenue stamp applied to and extending across the open end of said cover, an outer paper wrapper which seals the package, said inner wrapper having partly severed portions and tabs integral therewith and slits in end folds thereof, said outer wrapper having slits in end folds thereof, the slits in the inner wrapper occurring beneath said stamp, the slits in the outer wrapper occurring substantially coincident with one edge of said stamp, said tabs being extended outwardly through the slits in the inner and outer wrappers to present protruding ends exteriorly of the package, whereby a pull on said protruding ends in opposite direction will first break the outer wrapper, then break the stamp, and detach the partly severed portion, to form an opening in the package through which the contents of the package may be removed.
3. A package of the class described including an inner paper wrapper completely enveloping the contents of the package, said wrapper having lines of perforations in folds thereof and slits joining said lines to present partly severed portions, each of said portions having an integral tab, said tabs being extended through said slits to present protruding ends exteriorly of the package in its sealed and wrapped condition, whereby a pull on the protruding ends of the tabs will break the seal of the package, and will also detach said partly severed portions, to form an opening in the package through which the contents of the package may be removed.

OTTO T. MAURER.
